237,705

LETTERING AND WRITING PEN

Charles Roger Anderson, 20 East St.,
Proctor, Vt. 05765

Filed Feb. 8, 1973, Ser. No. 330,611

Term of patent 14 years

Int. Cl. D19—06

U.S. Cl. D19—45

FIG. 1 is a perspective view of a lettering and writing pen showing my new design;

FIG. 2 is a front elevation view;

FIG. 3 is a bottom plan view;

FIG. 4 is a right side elevational view;

FIG. 5 is a rear elevational view;

FIG. 6 is a top plan view;

FIG. 7 is an inverted left side elevational view, as seen looking at FIG. 3 from the left side; and

FIG. 8 is an enlarged cross-sectional view taken through the plane 8—8 in FIG. 4.

I claim:

The ornamental design for a lettering and writing pen, as shown and described.
